ABSTRACT OF THE DISCLOSURE

Antimicrobial long chain symmetrical tetrakisquaternary ammonium compounds are disclosed which have 15 the formula:

wherein R is an alkyl of C₁₀ to C₂₀; R', R'', and R''' are 20 each alkyl of C₁ to C₄ or aralkyl; x is 3 to 10; y is 2 to 10, and A is an anion.

The present application is a continuation-in-part of 25 applicant's copending patent application S.N. 494,948, filed Oct. 11, 1965, now abandoned.

The present invention relates to novel long chain symmetrical tetrakisquaternary ammonium compounds and, more particularly to long chain symmetrical tetrakisquaternary ammonium compounds having anti-microbial properties.

The preparation of polyquaternary ammonium compounds per se is not novel. On the other hand, all polyquaternary ammonium compounds are not anti-microbial. For example, Lewis et al. have reported in the British Journal of Pharmacology 20, 307-18 (1963) that short chain tetrakisquaternaries are neuromuscular blocking agents. G. Sykes has shown that the presence of serum interferes with the anti-microbial capabilities of some quaternary ammonium salts. (Disinfection and Sterilization, page 296, D. Van Nostrand, Princeton, N.J. 1958.) Consequently, while many U.S. patents provide descriptions of quaternary ammonium compounds which are said to possess preserving and/or disinfecting, bactericidal and/or fungicidal properties, the capabilities of new quaternary ammonium compounds are not predictable a priori.

For example, in U.S. Patent No. 2,108,765 it is stated that alpha-dodecyloxy-beta-hydroxypropyl-diethylbenzyl-ammonium chloride in a concentration of 1:50,000 kills colibacteria within 10 minutes and staphylococci within 15 minutes. At the same concentration dodecyl-diethylbenzyl-ammoniumchloride kills colibacteria after 10 minutes and staphylococci after 2½ minutes. However, the description in this patent which issued about twenty years before the publication of Sykes treatise does not describe the effect of the presence of serum on the capabilities of these quaternary ammonium compounds.

In 1939 U.S. Patent No. 2,178,522 issued describing aliphatic polyamines prepared by hydrogenating a polymerized aliphatic nitrite. Of course, amines do not have the properties of quaternary ammonium compounds.

The germicidal properties of N-alkylated alkylene polyamines and their salts such as dodecyl-diethylene triamine, C₁₂H₂₅-NH-C₂H₄-NH-C₂H₄-NH₂, and hexadecyl-triethylene tetramine,

C₁₆H₃₃-NH-C₂H₄-NH-C₂H₄-NH-C₂H₄-NH₂
are described in U.S. Patent No. 2,246,524. While the phenol coefficients for a number of these polyamines are

given the presence of serum during the test is not indicated.

The bactericidal and/or fungicidal capabilities of numerous quaternary ammonium compounds or polyamine compounds are discussed in such U.S. patents as Nos. 2,261,002; 2,295,505; 2,375,853; 2,388,614; 2,454,547; 2,717,909; 2,818,434; 2,857,380; 2,879,200; and 3,079,436.

However, that all polyamine or quaternary ammonium compounds are not anti-microbial or fungicidal is manifest from the disclosures in U.S. Patent Nos. 2,918,464; 2,807,910; 3,009,761; and 3,064,039.

The quaternary ammonium compounds represented by the formula

wherein R' and R² are either each a phenyl group or they together form with the neighboring nitrogen atom a carbazole, a phenoxazine or a phenothiazine ring system or the sulphoxide or the sulphone of a phenothiazine ring system; n is an integer from 2 to 10; N⁺ is a quaternary nitrogen atom carrying two methyl or ethyl groups; N²⁺ is a quaternary nitrogen carrying at least one methyl or ethyl group and either two additional methyl or ethyl groups or forming a part of a pyrrolidine, piperidine or morpholine ring; Y is an alkylene chain having 2 or 3 carbon atoms; and A⁻ is an anion of an inorganic or organic acid are said to have the property of blocking ganglion transmission.

The polyquaternary ammonium compounds represented by the formula

wherein

40 X is ClCH₂CH₂CH₂ or

Y is Cl or

Hal is halogen, and

50 n is a number between 4 and 29

are useful in the after-treatment in the conventional manner of dyed textiles.

The fact that a priori determination of the capabilities 55 of the polyammonium compounds is not possible is further illustrated by the peculiarities of the polyquaternary ammonium compounds described in U.S. Patent No. 2,807,910. These polyquaternary ammonium compounds, the formulae of thirty-eight of which are given by the patentees, are said to react with the soil particles and tend to bind individual particles into aggregates of larger size which no longer possess the colloidal properties of clay when wet and hence are useful for conditioning clay soil for agricultural purposes.

In view of the foregoing brief recital of the capabilities 65 of some polyquaternary ammonium compounds it is manifest that one skilled in the art cannot determine from the formula of the quaternary the capabilities thereof.

The novel polyquaternary ammonium compounds of 70 the present invention are represented by the formula

where R is a long alkyl chain, straight or branched, having 10 to 20 inclusive carbon atoms; R', R'', R''' are alkyl chains having one to four carbon atoms or aralkyl groups; A is an anion such as Cl, Br, I, CH_3COO —, $-\text{CH}_3\text{SO}_4$, x is three to ten inclusive; and y is 2 to 10 inclusive. For R' and R'' the preferred aralkyl groups are phenalkyl radicals having 1-2 carbon atoms in the alkyl group and for R''' the preferred aralkyl groups are phenalkyl radicals having 1-8 carbon atoms in the alkyl group as illustrated by the specific examples appearing below. It is to be observed that since R is the same alkyl group having 10 to 20 inclusive carbon atoms these polyquaternary ammonium compounds are symmetrical polyquaternary ammonium compounds and particularly tetrakisquaternary ammonium compounds. As those skilled in the art know the symmetrical polyquaternary ammonium compounds are distinguished from the unsymmetrical polyquaternary ammonium compounds generally by the fact that the distinguishing substituents of the terminal quaternary ammonium nitrogens are different in the unsymmetrical quaternaries but the same in the symmetrical quaternaries.

It is an object of the present invention to provide a method of preparing symmetrical tetrakisquaternary ammonium compounds described hereinbefore. It is another object of the present invention to provide novel symmetrical tetrakisquaternary ammonium compounds described hereinbefore. It is a further object of the present invention to provide microbial agents comprising a pharmaceutical acceptable carrier and an effective amount of at least one symmetrical tetrakisquaternary ammonium compound described hereinbefore. It is also within the purview of the present invention to provide microbial agents comprising pharmaceutically acceptable carrier and an amount of at least one hereinbefore described tetrakisquaternary ammonium compound effective in the presence of serum against at least one *Staphylococcus aureus*, *Corynebacterium acne*, *Bacillus subtilis*, *Escherichia coli*, *Pseudomonas aeruginosa*, *Candida albicans*, *Trichlorophyton mentagrophytes*, and *Aspergillus niger*. These and other objects of the present invention will become apparent to those skilled in the art from the following description of the present invention.

Illustrative of the preparation of the tetrakisquaternary ammonium compounds hereinbefore described and the microbial capabilities of the tetrakisquaternary ammonium compounds of the present invention is the following.

EXAMPLE I

Compound A represented by the formula

where R is dodecyl, R'' is methyl, x and y each is three, i.e.,

is prepared by refluxing for twenty minutes 0.02 mol of dodecyl-dimethyl(3-bromopropyl) ammonium bromide and 0.01 mol of N,N,N',N'-tetramethylethylenediamine in 30 milliliters of methyl ethyl ketone. A precipitate formed which is separated from the reaction mixture by filtration. The filter cake is washed with water and dried. After recrystallization from acetone-methanol the crystalline product melts at 206°-210° C.

The calculated nitrogen and bromine contents of $\text{C}_{12}\text{H}_{25}\text{NMe}_2(\text{CH}_2)_3\text{NMe}_2(\text{CH}_2)_2\text{NMe}_2(\text{CH}_2)_3\text{NMe}_2\text{C}_{12}\text{H}_{25}\text{Br}_4$

are respectively 5.92 percent and 33.76 percent. On analyzing the recrystallized reaction product for nitrogen and bromine concentrations of 5.71 percent and 33.38 percent respectively are found. By paper chromatography the re-

crystallized reaction product is shown to be different from the starting material and the bisquaternary

From the foregoing it is concluded that the recrystallized reaction product obtained as described hereinbefore (Compound A) is represented by the formula

EXAMPLE II

In a similar manner the tetrakisquaternary ammonium compound (Compound B) is represented by the formula

and is prepared from dodecylidimethyl(4-bromobuyl) ammonium bromide and N,N,N',N'-tetramethylethylenediamine. The recrystallized reaction product melts at 205° C. to 207° C., and contains 5.46 percent nitrogen and 32.36 percent bromine. The nitrogen and bromine concentrations for $\text{C}_{42}\text{H}_{94}\text{N}_4\text{Br}_4$ calculate to be 5.77 and 32.93 percent respectively. From which it is concluded that the recrystallized reaction product is represented by the formula

The anti-microbial activity of the symmetrical tetrakisquaternary ammonium compounds of the present invention in which the cationic moiety is represented by the formula

where R, R', R'', R''' x, y have the significance given hereinbefore is illustrated by the anti-microbial activity of compound A, i.e.,

and the anti-microbial activity of compound B, i.e.,

The anti-microbial activity is measured in test tube serial dilution test in the absence and in the presence of serum. The numerical values set forth in the following tabulation are minimum effective concentrations in micrograms per milliliter (g./ml).

Organism	1	2	3	4	5	6	7	8
Compound A	3.13	12.5	1.25	25	25	6.25	31.3	31.3
Compound A with 10% serum		12.5	25	6.25		25		
Compound B	12.5	12.5	3.13	12.5	25	6.25	31.3	15.6
Compound B with 10% serum	25	25	6.25	100	-----	50	-----	-----

Organisms—1. *Staphylococcus aureus*; 2. *Corynebacterium acne*; 3. *Bacillus subtilis*; 4. *Escherichia coli*; 5. *Pseudomonas aeruginosa*; 6. *Candida albicans*; 7. *Trichophyton mentagrophytes*; 8. *Aspergillus niger*.

As is to be anticipated the anti-microbial activity is not uniform with all of the tested organisms and each compound does not exhibit anti-microbial activity of the same order against each organism. For example, compound A is effective against *staphylococcus aureus* in the absence of serum at a minimum concentration of 3.13 micrograms per milliliter whereas compound B is effective against the same organism in the absence of serum only at a concentration about 4 times that of compound B. On the other hand, compound B is effective against *Escherichia coli* in the absence of serum in a minimum concentration of 12.5 micrograms per milliliter whereas compound A is only effective against the same organism in concentrations twice that of compound B. While both compound A and compound B retain their efficacies in the presence of serum it is of interest that serum has a greater apparent affect on one compound than on the other. For example, the minimal concentration of compound A must

be quadrupled to obtain an effective concentration against *Staphylococcus aureus* in the presence of serum whereas the concentration of compound B need only be doubled. Whereas compound A is effective against *Bacillus subtilis* in the absence of serum in a minimal concentration of 1.25 micrograms per milliliter and compound B is effective in a minimal concentration of 3.13 micrograms per milliliter in the presence of serum both compound A and compound B are effective at the same minimal concentration of 6.25 micrograms per milliliter.

These results indicate the substantial activity of these compounds. What is of at least as great importance is that a substantial proportion of the activity of these compounds is manifested in the presence of ten percent of serum which as reported by G. Sykes (*ibid*) interferes with the performance of some quaternary ammonium anti-microbials.

EXAMPLE III

Example I is repeated except that in place of 0.02 mol of the dodecyl quaternary compound there are used, in separate preparations, 0.02 mols of the following:

- (A) decyl dimethyl(3-bromopropyl)ammonium bromide
- (B) hexadecyl dimethyl(3-bromopropyl)ammonium bromide
- (C) eicosyl dimethyl(3-bromopropyl)ammonium bromide
- (D) decyl diethyl(3-bromopropyl)ammonium chloride
- (E) tetradecyl diisopropyl(3-bromopropyl)ammonium bromide
- (F) octadecyl di-n-butyl(3-bromopropyl)ammonium bromide
- (G) dodecyl diethyl(6-bromo-n-hexyl) ammonium bromide
- (H) hexadecyl di-n-propyl(10-bromo-n-decyl) ammonium bromide
- (I) dodecyl dibenzyl(3-bromopropyl)ammonium bromide
- (J) tetradecyl di-phenethyl(4-bromobutyl)ammonium bromide

EXAMPLE IV

Example I is again repeated except that the diamine is replaced (same mols) in separate preparations, by the following:

- (A) N,N,N',N'-tetraethyl ethylenediamine
- (B) N,N,N',N'-tetraisopropyl ethylenediamine
- (C) N,N,N',N'-tetrabenzyl ethylenediamine
- (D) N,N,N',N'-tetramethyl propylenediamine
- (E) N,N,N',N'-tetra-n-butyl ethylenediamine
- (F) N,N,N',N'-tetra-n-butyl butylenediamine
- (G) N,N,N',N'-tetra-n-butyl decylenediamine
- (H) N,N,N',N'-tetramethyl nonylenediamine
- (I) N,N,N',N'-tetrabenzyl hexylenediamine
- (J) N,N,N',N'-tetraphenethyl pentylenediamine

EXAMPLE V

Examples IIIA, IIIC, IIIF and IIIH are each repeated except that in place of the diamine used in those examples there are used in separate preparations equimolar amounts of the following:

- (A) N,N,N',N'-tetraethyl ethylenediamine
- (B) N,N,N',N'-tetraethyl butylenediamine
- (C) N,N,N',N'-tetraethyl nonylenediamine
- (D) N,N,N',N'-tetra-t-butyl propylenediamine
- (E) N,N,N',N'-tetra-t-butyl decylenediamine
- (F) N,N,N',N'-tetrabenzyl hexylenediamine
- (G) N,N,N',N'-tetraphenethyl hexylenediamine
- (H) N,N,N',N'-tetraphenoxyethyl ethylenediamine

Although the present invention has been described with reference to particular embodiments and examples, it will be apparent to those skilled in the art that variations and modifications of this invention can be made and that equivalents can be substituted therefor without departing from the principles and true spirit of the invention.

What is claimed is:

1. Tetrakisquaternary ammonium compounds having the following formula:

wherein R is an alkyl of C₁₀ to C₂₀; R' and R'' are each alkyl of C₁ to C₄ or phenalkyl having 1 to 2 carbon atoms in the alkyl group; R'''' is an alkyl of C₁ to C₄ or phenalkyl having 1-8 carbon atoms in the alkyl group; x is to 3 to 10; y is 2 to 10; and A is an anion selected from the group consisting of chloride, bromide, iodide, acetate and methylsulfate.

2. A compound, as defined in claim 1 wherein R is dodecyl; R', R'' and R'''' are each methyl; x is 3; and y is 3.

3. A compound as defined in claim 1 wherein R is dodecyl; R', R'' and R'''' are each methyl; x is 4; and y is 4.

4. A compound as defined in claim 2 wherein A is bromine.

5. A compound as defined in claim 3 wherein A is bromine.
